HYDRAULIC ADJUSTING DEVICE

Cecil F. Badgley, Bozeman, Mont.

Application October 28, 1955, Serial No. 543,384

7 Claims. (Cl. 309—26)

This invention relates to hydraulic jack devices, and more particularly to a hydraulic jack device suitable for use in adjusting the tension of vehicle tracks.

A main object of the invention is to provide a novel and improved hydraulic jack device for use in adjusting the tension of the tracks of track-laying vehicles, said jack device being simple in construction, being easy to operate, and being suitable generally for use in lifting or adjusting relatively heavy loads by means of grease or oil pressure, or the like.

A further object of the invention is to provide an improved hydraulic jack device which is inexpensive to fabricate, which is rugged in construction, which is suitable for general use for lifting or adjusting relatively heavy loads by means of hydraulic pressure, for example, by means of grease or oil pressure, and which is easy to operate, as by the use of a conventional grease gun, or the like.

Further objects and advantages of the invention will become apparent from the following description and claims, and from the accompanying drawings, wherein:

Figure 1 is a side elevational view of an improved hydraulic jack device constructed in accordance with the present invention, shown applied to a track-laying vehicle, and arranged so that it may be employed for adjusting the tension of the track of the vehicle.

Figure 2 is an enlarged longitudinal vertical cross sectional view taken through the jack device of Figure 1.

Figure 3 is a transverse vertical cross sectional view taken on the line 3—3 of Figure 2.

Figure 4 is a longitudinal vertical cross sectional view taken through a modified form of jack device according to the present invention.

Figure 5 is a transverse vertical cross sectional view taken on the line 5—5 of Figure 4.

Figure 6 is a transverse vertical cross sectional view taken on the line 6—6 of Figure 4.

Referring to the drawings, and more particularly to Figures 1, 2 and 3, 11 designates a hydraulic jack device, for example, a jack device which is mounted on a track-laying vehicle and arranged for adjusting the tension of the track 12 of the vehicle. The hydraulic jack device 11 comprises a cylinder 13 which is secured in any suitable manner to a portion 14 of the frame of the vehicle. Designated at 15 is a piston rod which is secured in any suitable manner to the axle bearing assembly 16, the piston rod 15 being aligned with the cylinder 13 and being threadedly engaged with a piston 17 which is slidably received in the cylinder, as is clearly shown in Figure 2.

The piston 17 is reduced at 18, and the cylinder bore is similarly reduced at 19 to slidably receive the reduced piston portion 18.

Designated at 20 is a circular sealing element, which may be generally cup-shaped, as shown in Figure 2, said sealing element being relatively deformable and being centrally secured to the end of the reduced piston portion 18, as by a bolt 21. The reduced portion 18 is formed at its end with the conically tapered member 22,

2

and surrounding the tapered member 22 is the annular ring member 23 of relatively expandable material, such as relatively soft metal, or the like, the ring 23 being formed with a tapered conical bore 24 receiving the tapered member 22. A sealing ring 25 of rubber or similar resilient deformable material is seated in an annular groove provided in the tapered member 22 to provide a fluid tight seal between the ring 23 and the member 22. A similar sealing ring 26 of resilient deformable material is seated in an annular groove provided in the outer surface of the ring 23 and provides a fluid tight seal between ring 23 and the inside surface of the reduced portion 19 of the cylinder wall.

Designated at 27 is a grease inlet fitting which is mounted in the end portion of the cylinder wall facing the piston sealing member 20, as shown in Figure 2, the inlet fitting 27 being provided with a check ball 28 which prevents the discharge of grease from the fitting after said grease has been forced into the cylinder. Opposite the grease fitting 27 the cylinder wall is formed with a tapped bore 29 in which is engaged a threaded plug 30. A passage 31 connects the interior of the cylinder with the bore 29, and a valve ball 32 is provided in the bore 29, said ball being held on the seat defined by the opening 31 by the threaded plug 30 when said plug is tightened. A discharge passage 33 is provided in the end wall of the cylinder, said passage communicating with the bore 29, and allowing grease to discharge therethrough from the cylinder when the plug 30 is loosened.

When it is desired to increase the tension of the vehicle track 12, grease is pumped into the cylinder by means of a suitable implement such as a grease gun, or the like, applied to the grease fitting 27, the grease acting against the piston sealing member 20 and the pressure thereof being transmitted to the deformable annular sealing ring 23 which wedgingly engages against the tapered member 22 of the piston 18. The wedging action thus exerted causes the ring 23 to expand and to provide a tight metal-to-metal seal between the piston portion 18 and the inside surface of the cylinder, while at the same time allowing the piston to be moved the amount necessary to provide the desired tension in the track 12. The grease will be retained in the cylinder because of the closing of the check valve ball 28 against the grease inlet opening of the fitting 27 when the grease gun is removed, whereby the tension in the track 12 will be maintained. In order to loosen the track, it is merely necessary to unscrew the plug 30, whereby the ball 32 will be forced off of its seat allowing grease to discharge from the cylinder through the passage 33.

Referring now to Figures 4, 5 and 6, a modified form of jack device, suitable for use as a vehicle track adjuster, or for any other purpose, is disclosed, the jack device being designated generally at 11' and comprising a cylinder 13' which is of relatively large diameter and which is formed with an elongated portion 14' of substantially smaller diameter arranged axially with respect to the enlarged main portion of the cylinder, as shown. A piston, designated generally at 15' has a relatively large main body portion 16' slidably received in the enlarged main portion of cylinder 13' and has a reduced extension 17' slidably received in the reduced cylinder portion 14'. Between the enlarged main portion 16' and the reduced extension 17' of the piston, the piston is formed with the conically tapered neck member 18' on which is engaged the sealing ring member 19' of relatively expandable metal, the ring 19' being formed with the conically tapered bore 20' engaging on the tapered neck member 18', as shown in Figure 4. A sealing ring 21' of rubber or similar deformable resilient material is seated in an annular groove formed on the tapered member 18' to provide a fluid-tight seal between the

neck member 18' and the bore 20'. Additional annular sealing rings 22' are seated in spaced annular grooves formed in the outer surface of the ring member 19' to provide a fluid-tight seal between the ring 19' and the inside surface of the enlarged main portion of the cylinder 13'.

Designated at 23' is a conically tapered member formed at the end of the reduced piston portion 17', said conically tapered member having secured thereto the circular sealing cup 24', as by the hollow bolt 25'. A sealing ring 26' of deformable resilient material is seated in an annular groove formed in the conically tapered member 23'. Designated at 27' is a ring member of relatively soft metal, similar to the material employed for the ring member 19', said ring member being formed with a tapered bore 28' in which the tapered member 23' is received and which is sealed with respect thereto by the sealing ring 26'. A sealing ring 28' of deformable resilient material is seated in an annular groove formed in the outer surface of the ring 27', the sealing ring 28' providing a fluid tight seal between the ring member 27' and the inside surface of the reduced portion 14' of the cylinder.

The piston 17' is formed with an axial bore 30' which communicates with the bore 31' of the hollow bolt 25' and which is in communication with a laterally directed passage 32' formed in the end portion of piston member 17' adjacent the neck member 18', the passage 32' communicating with the space 33' between the ring 19' and the shoulder portion 34' of the cylinder. The space 33' is thus in communication with the space 35' between the sealing member 24' and the end wall 36' of the reduced cylinder member 14'.

A grease fitting 37' is provided in the wall of the enlarged portion of the cylinder 13' adjacent the shoulder wall 34', as shown in Figure 5. Opposite the fitting 37', the wall of the cylinder is provided with the release plug 38' which controls the closure of a valve ball 39' on the opening 40' connecting space 33' with the bore of the plug 38', the shoulder wall 34' being provided with a discharge passage 41' communicating with the bore of the plug 38' through which grease may discharge from the space 33' when the plug 38' is loosened to allow the valve ball 39' to unseat.

As in the previously described form of the invention, grease is pumped into the space 33', as by the use of a suitable grease gun, the grease filling the space 33' and flowing through passage 32', bore 30' and the hollow bolt 25' into the space 35', the combined pressures of the grease material acting on the member 24' and on the ring 19' to expand the expandable ring elements 27' and 19' to provide a close, fluid tight seal between said members 19' and 27' and the adjacent surfaces of the cylinder wall. By providing the piston extension 17', the main piston portion 16' is maintained accurately centered, and tilting or misalignment thereof is effectively prevented.

The expandable ring member 23 in the embodiment of the invention shown in Figures 1, 2 and 3, and the expandable ring members 19' and 27' in the embodiment of the invention shown in Figures 4, 5 and 6, are preferably made of suitable relatively soft metal, such as aluminum, brass, or the like, these metals being considerably softer than the material of which the pistons are made which is ordinarily steel. The cup members 20 in Figures 1, 2 and 3, and 24' in Figures 4, 5 and 6, are preferably made of leather, neoprene, or similar deformable material.

While certain specific embodiments of an improved hydraulic jack device have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a hydraulic jack device of the character described, a cylinder, a piston in said cylinder, a piston sealing member aligned with said piston, a tapered member at the end of said piston adjacent said piston sealing member, means connecting said piston sealing member to said piston, an expandable ring member surrounding said tapered member and disposed between the piston sealing member and said tapered member, the outer portion of said ring member sealingly engaging the inside surface of the cylinder, said outer portion being formed with a circumferential annular groove, and a sealing ring of resilient deformable material in said groove.
2. In a hydraulic jack device of the character described, 15 a cylinder, a piston in said cylinder, a tapered member at the end of said piston, an expandable ring member surrounding said tapered member and wedgingly engaging said tapered member, the outer portion of said ring member sealingly engaging the inside surface of the cylinder, 20 said outer portion being formed with a circumferential annular groove, and a sealing ring of resilient deformable material in said groove.
3. In a hydraulic jack device of the character described, 25 a cylinder, a piston in said cylinder, a piston sealing member aligned with said piston, a tapered member at the end of said piston adjacent said piston sealing member, a ring member disposed on said tapered member and being arranged between said tapered member and said piston sealing member, said ring member being of relatively deformable material and being expandable into sealing engagement with the inside surface of the cylinder responsive to thrust exerted by the piston thereon, the outer surface portion of the ring member being formed with a circumferential groove, and a sealing ring of resilient 30 deformable material in said groove.
4. In a hydraulic jack device of the character described, 35 a cylinder, a piston in said cylinder, a piston sealing member aligned with said piston, a tapered member at the end of said piston adjacent said piston sealing member, means connecting said piston sealing member to said piston, a ring member disposed on said tapered member and being arranged between said tapered member and said piston sealing member, said ring member being of relatively soft metal and being expandable into sealing engagement with the inside surface of the cylinder responsive to thrust exerted by the piston thereon, the outer surface portion of the ring member being formed with a circumferential groove, and a sealing ring of resilient 40 deformable material in said groove.
5. In a hydraulic jack device of the character described, 45 a cylinder, a piston in said cylinder, a piston sealing member slidably mounted in said cylinder in alignment with said piston, a tapered member at the end of said piston adjacent said piston sealing member, axial bolt means connecting said piston sealing member to said piston, a ring member disposed on said tapered member and being arranged between said tapered member and said piston sealing member, said ring member having a tapered internal bore receiving said tapered member 50 and being of relatively soft metal, said ring member being expandable into sealing engagement with the inside surface of the cylinder responsive to thrust exerted by the piston thereon, the outer surface portion of the ring member being formed with a circumferential groove, and a sealing ring of resilient deformable material in said groove.
6. In a hydraulic jack device of the character described, 55 a cylinder having a main bore and a relatively smaller auxiliary bore closed at its end and axially aligned with said main bore, a main piston in said main bore, a reduced piston element in said auxiliary bore, a tapered portion rigidly connecting said main piston to said reduced piston element, a second tapered portion on the end of said reduced piston element, respective expandable ring members on said tapered portions wedgingly 60
7. In a hydraulic jack device of the character described, 65 a cylinder having a main bore and a relatively smaller auxiliary bore closed at its end and axially aligned with said main bore, a main piston in said main bore, a reduced piston element in said auxiliary bore, a tapered portion rigidly connecting said main piston to said reduced piston element, a second tapered portion on the end of said reduced piston element, respective expandable ring members on said tapered portions wedgingly 70
8. In a hydraulic jack device of the character described, 75 a cylinder having a main bore and a relatively smaller auxiliary bore closed at its end and axially aligned with said main bore, a main piston in said main bore, a reduced piston element in said auxiliary bore, a tapered portion rigidly connecting said main piston to said reduced piston element, a second tapered portion on the end of said reduced piston element, respective expandable ring members on said tapered portions wedgingly

engageable with the inside surfaces of the main bore and auxiliary bore, and a deformable sealing cup on the end of said second tapered portion, said reduced piston element and its tapered portion being formed with a passage opening at one end into the closed end of the auxiliary bore and opening at its other end into the space in the main bore adjacent the expandible ring member on the tapered portion connecting the main piston to said reduced piston element, said cylinder being provided with passage means in its wall for the admission of pressure fluid into the cylinder.

7. In a hydraulic jack device of the character described, a cylinder having a main bore and a relatively smaller auxiliary bore closed at its end and axially aligned with said main bore, a main piston in said main bore, a reduced piston element in said auxiliary bore, a tapered portion rigidly connecting said main piston to said reduced piston element, a second tapered portion on the end of said reduced piston element, sealing means on the tapered portions, and a deformable sealing cup on the 20

end of said second tapered portion, said reduced piston element and its tapered portion being formed with a passage opening at one end into the closed end of the auxiliary bore and opening at its other end into the space in the main bore adjacent the sealing means on the tapered portion connecting the main piston to said reduced piston element, said cylinder being provided with passage means in its wall for the admission of pressure fluid into the cylinder.
